CLAIM

The ornamental design for a perfume bottle, as shown and described.

DESCRIPTION

FIG. 1 is a front elevational view of a perfume bottle, showing my new design;

FIG. 2 is a left-side elevational view thereof;

FIG. 3 is a right-side elevational view thereof;

FIG. 4 is a cross-sectional view thereof, showing a section taken along line 4-4 of FIG. 5;

FIG. 5 is a top plan view thereof;

FIG. 6 is a bottom plan view thereof;

FIG. 7 is a top, front, left-side perspective view thereof; and,

FIG. 8 is a rear elevational view thereof.

The broken lines in FIGS. 4, 5, and 7 depict portions of the perfume bottle that form no part of the claimed design.

1 Claim, 8 Drawing Sheets
